ATTORNEY

UNITED STATES PATENT OFFICE.

JOHN D. EMACK, OF BALDWIN, NEW YORK.

SCHOOL-SLATE.

SPECIFICATION forming part of Letters Patent No. 288,698, dated November 20, 1883.

Application filed July 30, 1883. (No model.)

To all whom it may concern:

Be it known that I, JOHN D. EMACK, of Baldwin, Queens county, New York, have invented certain Improvements in the Construction of School-Slates; and I do hereby declare that the following is a clear and correct description of my invention, reference being had to the accompanying drawings, making part of this specification, and to the letters of reference marked thereon, in which—

Figure 1 is a perspective view of my improved slate and frame. Fig. 2 is a transverse section through the center of the circular depressions or guide-marks, showing the form of these depressions and of the grooves in the sides of the frame.

In the drawings like parts of the invention are designated by the same letters of reference.

The nature of the present invention relates to improvements in the construction of slates, for use in schools more particularly; and it consists in providing the slate-frames, upon each edge, with a short groove placed about centrally, and also with the circular depressions upon the upper and under sides of the frame, the object of the invention being the production of a slate which can easily be lifted from the desk or table upon which it is usually placed and turned over without the usual noise occasioned by turning a slate over upon a desk or table.

Noiseless slates are common; but in about all in use they are so rendered by the employment of rubber cushions, or by winding the frame with flannel, twine, or some fibrous or textile material. In some cases the frame has been coated with a composition of matter somewhat of the nature of rubber, or a frame not made of wood, but molded from a composition of matter, has been employed.

To enable those skilled in the arts to use my invention, I will describe the same.

A shows the bars or sections of wood employed to form the frame, constructed and united in the usual manner, the inner edge of 45 the same being grooved to receive the edges of the slate B. Upon the outer edges of the longitudinal bars I place, about centrally, the short grooves C, and upon the upper and under sides of these longitudinal bars I place the 50 circular depressions D.

The operation may be thus set forth. The grooves C are intended to receive two or more of the upper portions of the fingers of the pupil, while the circular depressions receive the 55 upper portion of the thumbs, or may serve as indicants for the pupil to find the grooves C. The upper portion of two or more of the fingers having been inserted in the grooves C, and the upper portion of the thumbs resting 60 in the circular depressions D, the slate may be removed from the desk or table, turned over and replaced upon the desk or table noiselessly, or without the accompaniment of the noise usually attending the turning over of 65 a slate upon a desk or table.

The cost of grooving the frame and forming the depressions in the same is so slight that the cost of the slate is but little increased.

What I claim as new, and desire to secure by 70 Letters Patent, is—

A slate-frame provided with the grooves C and circular depressions D, substantially as and for the purpose indicated.

JOHN D. EMACK.

In presence of—

A. SIDNEY DOANE,
WILLIAM V. H. HICKS.
